UNITED STATES PATENT OFFICE.

ELMORE A. BARNES, OF PITTSBURG, PENNSYLVANIA.

ROLLS FOR ROLLING SHOVEL-BLANKS.

SPECIFICATION forming part of Letters Patent No. 267,822, dated November 21, 1882.

Application filed May 15, 1882. (No model.)

To all whom it may concern:

Be it known that I, ELMORE A. BARNES, of Pittsburgh, in the county of Allegheny and State of Pennsylvania, have invented an Improvement in Rolls for Rolling Shovel-Blanks; and I do hereby declare that the following is a full and exact description thereof, reference being had to the accompanying drawings, making part of this specification—

10 Figure 1 being a top view of my improved rolls properly mounted and with the operative parts connected therewith; Fig. 2, an end view of the same; Fig. 3, a transverse vertical section thereof in a plane indicated by the line α α , Fig. 1; Fig. 4, a transverse section of the rolls only; showing a different portion of the same from that shown in Fig. 1 or in Fig. 3.

Like letters designate corresponding parts in all of the figures.

20 My improved rolls are specially designed for use in carrying out the main part of my improved process of rolling shovel-blanks, for which I have made application for Letters Patent of the same date as this application; but 25 I do not restrict the present invention solely to that use, but claim it for any other use to which its principle is applicable.

The object of the invention is to construct 30 a pair of reducing or shaping rolls between which the blank to be shaped may be inserted or fed in from the discharging or opening side of the rolls, instead of feeding in from the opposite, closing side thereof. By such a construction I am enabled, with continuously-revolving 35 rolls, to pass a portion only of the shovel-blank between the rolls, leaving the remaining portion untouched for shaping between other rolls or not.

The rolls represented in the drawings, and 40 the construction of which I herein describe, are adapted to shaping the blades of shovel-blanks formed from one piece of metal. It being required to give an additional thickness of metal over the socket part of the blade of the shovel, I produce this re-enforced portion by 45 the rolls herein described without requiring the usual hammering of the same. The two rolls are situated so that their peripheries are nearly in contact, allowing just sufficient space 50 between them to produce the general thickness of the shovel-blades. Means for adjusting the distance between them is provided to

allow for any desired variation in the thickness of the shovel-blades, and to admit of passing the blanks more than once between the 55 rolls when it is desirable to reduce the thickness of the blanks by successive rollings.

The lower roll, A, in the accompanying drawings is shown as a simple plain roll. The upper roll, B, has a depression, a , of the proper 60 shape and depth to give the additional thickness or re-enforcement required over the socket part of the shovel-blade by reducing the remaining part of the blade to its ultimate thinness. As the blank X is to be inserted 65 between the rolls from the discharging side, as indicated in Fig. 3, the strap end w thereof, by which the blank is handled, pointing to that side, it is necessary to furnish a space between the rolls. To enable this mode of insertion to 70 be accomplished, I make a large notch or cut-away opening, b , in this upper roll, B, as shown in the drawings, wide and deep enough for the purpose, and of sufficient extent around the periphery of the roll to allow sufficient time to 75 insert a blank properly while the rolls are revolving, say, one-third of the circumference of the roll, more or less. This is, in position, just in advance of the depression a , as the roll revolves in the direction shown by the arrows 80 in Figs. 3 and 4. As seen in Fig. 3, the blank X has just been inserted and placed in such a position as to have the rolls act upon the upper end of the blade, next to the strap portion first, and finish at the lower end. In Fig. 4 I 85 have shown the rolls as somewhat further advanced and in the act of reducing the blanks.

There might be a depression in the lower roll, A, similar to the depression a in the roll B, so as to throw a part of the shaping on both 90 sides, but this is not necessary; and a part of the feeding-in space might be cut in the lower roll, which also is unnecessary. By shaping only one roll, B, for the purpose I am able to make the other roll a simple plain one, as 95 shown. Then the two rolls do not require to move accurately in time with each other, and it is not necessary even to gear them together. I have, however, represented them as geared together by cog-wheels d f . 100

Generally I pass the shovel-blade twice or more between the rolls, reducing partially the first time and completing the reduction the second time. I have shown a known means of

adjusting the roll B toward the roll A, the screws C C, which press upon the top bearings, D D, of the roll B, having notched disks E E on their upper ends, into which two radially-extended levers, G G, pivoted on the respective screw-heads, engage, as shown. The two levers are placed in parallel positions, and have a connecting bar or rod, g, so that as one turns the other turns equally in the same direction. One of the levers is extended to form a handle, h. By turning back the levers to the position shown by full lines in Fig. 1, the rolls may be properly separated for the first action on the blank. Then by shifting the levers to a position indicated by dotted lines in the same figure the rolls will be in position for the second action on the blank.

I have shown and described the construction of the rolls for reducing the shovel-blade.

A similar construction, except as to the form of the depression where additional thickness is required, serves for reducing the strap part of the shovel-blank in the same way; and this construction is adapted to reducing other arti-

cles or blanks where it may be required or desired to act on a part thereof without passing the whole between the rolls. The rolls, having a continuous uniform revolving movement, require only the simplest means for their operation. The work is also done with great facility and all practicable rapidity.

What I claim as my invention, and desire to secure by Letters Patent, is—

A pair of continuously-revolving rolls, A B, for rolling and re-enforcing shovel-blanks, one roll being provided with a re-enforcing depression, a, and one of the rolls having a depression, b, in advance of the depression a, and of such depth and peripheral extent as to enable the blanks to be inserted between the rolls from the discharge side thereof while they are revolving, substantially as and for the purpose herein specified.

ELMORE A. BARNES.
